United States Patent Office

Des. 231,405
Patented Apr. 16, 1974

231,405

MARKER BUOY

Buyrl A. Franks, Tulsa, Okla., assignor to Lowrance
Electronics, Inc., Tulsa, Okla.

Filed Oct. 20, 1971, Ser. No. 191,141

Term of patent 14 years

Int. Cl. D10—06

U.S. Cl. D71—1 P

FIG. 2

FIG. 1

FIG. 3

FIG. 1 is a side view of a marker buoy showing my new design, the opposite side appearing the same.

FIG. 2 is a top view of the marker buoy, the bottom appearing the same.

FIG. 3 is a view of one end of the marker buoy, the opposite end appearing the same.

I claim:

The ornamental design for a marker buoy, substantially as shown and described.
